DESIGN FOR A CONTAINER

Guy J. Banta, Los Angeles, Calif.

Application March 12, 1941, Serial No. 99,512

Term of patent 7 years

To all whom it may concern:

Be it known that I, Guy J. Banta, a citizen of the United States, residing at Los Angeles, in the county of Los Angeles and State of California, have invented a new, original, and ornamental Design for a Container, of which the following is a specification, reference being had to the accompanying drawing, forming a part thereof.

Fig. 1 is a front elevational view;
Fig. 2 is a side elevational view; and
Fig. 3 is a plan view of a container showing my new design.

I claim:
The ornamental design for a container, as shown.

GUY J. BANTA.
